(57) **CLAIM**

The ornamental design for a retroreflective and luminous article, as shown and described.

DESCRIPTION

FIG. 1 is a perspective view of a retroreflective and luminous article showing the new design. As shown, the pattern of dots between the generally diamond-shaped retroreflective segments is used to designate luminous background. The discrete dots are shown merely for illustration purposes and the area designated by the dots represents a uniformly illuminated area;

FIG. 2 is a top view thereof;

FIG. 3 is a bottom view thereof;

FIG. 4 is a side view thereof; and,

FIG. 5 is a perspective view of a retroreflective and luminous article shown in an alternate position of use.

The broken line drawing is for environmental disclosure and does not form part of the claimed design.
